ATTORNEY.

UNITED STATES PATENT OFFICE.

JOSEPH KACZMARCZYK, OF DETROIT, MICHIGAN.

DESIGN FOR A RAIL-CLAMP.

55,383.

Specification for Design.

Patented June 1, 1920.

Application filed October 22, 1919. Serial No. 332,568. Term of patent 3½ years.

To all whom it may concern:

Be it known that I, JOSEPH KACZMARCZYK, a citizen of Austria, and a resident of Detroit, in the county of Wayne and State of Michigan, have invented a new, original, and ornamental Design for a Rail-Clamp, of which the following is a specification, reference being had to the accompanying drawings, forming part thereof.

The figure is a perspective view of a rail clamp, showing my new design.

I claim:

The ornamental design for a rail clamp, as shown.

JOSEPH KACZMARCZYK.

Witnesses:

ANDREW LESNIAK,

FRANK BAVANSKI.
